UNITED STATES PATENT OFFICE

JOSEPH W. RANDALL, OF NORTH ANDOVER, MASSACHUSETTS, ASSIGNOR TO DAVIS & FURBER MACHINE COMPANY, OF NORTH ANDOVER, MASSACHUSETTS, A CORPORATION OF MASSACHUSETTS

SPINDLE DRIVE FOR SPINNING FRAMES

Application filed November 8, 1928. Serial No. 318,093.

This invention relates to a spindle drive for a spinning frame in which the spindles are driven in groups by bands driven in turn by a common driving drum. In such 5 spinning frames it is essential that all of the spindles in the frame shall be driven at the same speed and that the driving force transmitted from the band to each spindle shall be the same in order to produce yarn of the 10 same quality on all of the spindles. Furthermore, it is desirable to provide for reversing the twist in the yarn spun on a given frame whenever it may be required.

The object of the present invention is to 15 provide a drive of this type in which the twist may be reversed by reversing the rotation of the driving drum and in which the functioning of the drive upon the various spindles will be precisely the same irrespec- 20 tive of the direction of rotation of the driving drum.

The object of the invention is further to 25 provide a drive of this type in which, irrespective of the direction of rotation of the driving drum, the spindles shall be driven by the band pulling directly from the drum to the spindles in succession.

The object of the invention is further to 30 provide such a drive in which, irrespective of the direction of rotation of the driving drum, means are provided for maintaining the band under a constant tension and with the band pulling directly from the drum to the spindles in succession.

The object of the invention is further to 35 provide a construction which may readily be embodied in existing spinning frames, which is of a simple character, and which is readily adapted for producing either a right or left- 40 hand twist.

As the invention relates entirely to the 45 drive and is adapted to be embodied in various types of spinning frames, and as the general construction and operation of such spinning frames are well known and familiar to those skilled in the art, it is only necessary here to illustrate and describe, and then only in a very general way, those portions of one 50 type of spinning frame in which a preferred

and illustrative form of the present invention may be embodied.

In the drawings:

Fig. 1 is a top plan view illustrating somewhat diagrammatically a section of a driving drum, a set of four spindles, two at each side, and a drive embodying the invention arranged to produce a twist as indicated by the arrows. 55

Fig. 2 is a side elevation somewhat more in detail of a construction such as illustrated in Fig. 1. 60

Fig. 3 is a view similar to Fig. 1 showing the drive arranged to produce the opposite twist also indicated by the arrows. 65

Fig. 4 is a view of the same character as Fig. 2 of the construction illustrated in Fig. 3.

In the spinning frame illustrated, a portion of one of the end frame members 1 is shown. Between these end frames extend the rails 2 supporting at each side a row of spindles 3 and 4. The driving drum 5 of the usual type extends longitudinally of the frame midway between the two rows of spindles and is adapted to be driven, in accordance with common practice, in either direction according to the twist in the yarn desired. 70

The spindles are driven from the driving drum in groups, each group by a single band. Preferably, as illustrated, a group comprises two spindles 3 of the row at one side of the frame and two oppositely disposed spindles 4 of the row at the other side of the frame, so that the band 6 will engage a 90° segment 80 of the whirl of each spindle. 85

In this invention an idler 7 journaled on a suitable support 8 is provided to engage a loop in the band and take up slack. Means are also provided for mounting this support at either side of the driving drum as may be required by the direction of rotation of the driving drum and in order to secure precisely the same conditions controlling the drive in either case. In the specific construction illustrated for this purpose, a rod 9 is mounted at one side of the drum 5 and extends parallel therewith between the drum and the adjacent row of spindles 3, this rod being carried in suitable brackets 10 in the frames. Similarly 90

another rod 11 is mounted in a similar position at the other side of the drum parallel therewith and between the drum and the other row of spindles 4. The idler support 8, in the specific construction shown, is in the form of a bell crank lever having a fulcrum bearing 12 adapted to fit over either rod 9 or 11, having its depending arm formed in two parts 13 and 14 adjustably connected by a bolt 15, and having a horizontally extending arm 16 notched at 17 on its upper surface so that a weight 18 may be suspended on the arm at any desired distance from the fulcrum. Positioning collars 19 are adjustably mounted longitudinally of the rods 9 and 11 by means of set screws 20 and the fulcrum bearing 12 of the idler supporting lever is adapted to straddle one of these positioning collars thus to position the idler longitudinally of either rod as desired.

If, now, it is desired to spin with a twist indicated by the arrows in Fig. 1, the driving drum 5 will be rotated in the direction indicated by the arrows thereon in Figs. 1 and 2. The idler support will be placed on the rod 9 straddling the proper collar 19 with the idler 7 between the drum 5 and the row of spindles 3 and the belt will be passed about the drum, about the idler and about the spindles as illustrated. It will be seen that, starting with the driving drum 5, the band passes from the drum, in this case from the top of the drum, at a point 21 in a direction opposite to the pull given it by the drum and consequently in a direction opposite to the rotation of the drum, past the idler 7 and directly to and thence around in succession the group of four spindles, passing first around the spindles 3, then above the drum and around the spindles 4. From the last spindle the band passes around the idler 7 in the form of a loop, this loop standing between the drum 5 and the spindles 3 to which the band first passed. Thence from the idler 7 the band passes around the drum to the point 21 of beginning. It will thus be seen that the band drives with a pull directly from the drum to the spindles in succession.

Now when it is desired to place the opposite twist in the yarn, the direction of rotation of the driving drum 5 is reversed and the idler support is simply shifted over onto the opposite rod 11 with the loop in the band previously engaging the idler now engaging the drum and with the loop previously engaging the drum now engaging the idler. The drive is then in the position shown in Figs. 3 and 4. Again it will be seen that, starting with the driving drum 5, the band passes from the drum, in this case from the top of the drum, at a point 22 in a direction opposite to the pull given it by the drum and consequently in a direction opposite to the rotation of the drum, past the idler 7 and directly to and thence around in succession the group of

four spindles, passing first around the spindles 4, then above the drum and around the spindles 3. From the last spindle the band passes around the idler 7 in the form of a loop, this loop standing between the drum 5 and the spindles 4 to which the band first passed. Thence from the idler 7 the band passes around the drum to the point 22 of beginning. Again it will be seen that the band drives with a pull directly from the drum to the spindles in succession.

Thus it will be seen that by providing means for mounting the idler support at either side of the driving drum as desired with the band arranged as thus described, the band will always drive with a pull directly from the drum to the spindles in succession, irrespective of the direction of rotation of the drum.

The idler 7, by reason of the weight 18 adjustable along the arm 16, also provides a means by which it is yieldingly forced against the band, under either condition, to maintain a constant tension therein, and it will be seen that this tension will be the same, if the adjustment is the same, whether the twist be a right-hand twist or a left-hand twist, that is, whether the drum 5 be rotated in one direction or the other.

Having thus described the invention, what is claimed as new, and desired to be secured by Letters Patent, is:

1. A spindle drive comprising a driving drum rotatable in either direction according to the twist desired, a row of spindles at each side of the drum all arranged in groups each of which comprises oppositely disposed spindles, a support for each group having an idler journaled thereon, an endless band for each group passing from the drum in a direction opposite to the pull given it by the drum directly to and around the spindles of the group successively, thence forming a loop between the drum and the spindle to which it first passed, thence passing from said loop around the drum to the point of beginning and means for mounting each support with its idler in and engaging the loop of its corresponding band whereby, irrespective of the direction of rotation of the drum, each band will always drive with a pull directly from the drum to the spindles of its group in succession.

2. A spindle drive comprising a driving drum rotatable in either direction according to the twist desired, a row of spindles at each side of the drum all arranged in groups each of which comprises oppositely disposed spindles, a support for each group having an idler journaled thereon, means for mounting each support with its idler at that side of the drum away from which the top of the drum is rotated, and an endless band for each group passing from the top of the drum in a direction opposite to its rotation directly to and

around the spindles of the group successively, thence around the idler of its group and thence to the bottom of the drum and around the drum to the point of beginning whereby, irrespective of the direction of rotation of the drum, each band will always drive with a pull directly from the drum to the spindles of its group in succession.

3. A spindle drive comprising a driving drum rotatable in either direction according to the twist desired, a row of spindles at each side of the drum all arranged in groups each of which comprises oppositely disposed spindles, a rod at each side of the drum extending parallel therewith between the drum and the adjacent row of spindles, a support for each group having an idler journaled thereon, means for mounting each support on that rod away from which the top of the drum is rotated, an endless band for each group passing from the top of the drum in a direction opposite to its rotation past the idler of the group and directly to and around the spindles of the group successively, thence past the drum around the said idler and thence to the bottom of the drum and around the drum to the point of beginning, and means for yieldingly forcing each idler against its band to maintain a constant tension therein whereby, irrespective of the direction of rotation of the drum, each band will always drive under a constant tension and with a pull directly from the drum to the spindles of its group in succession.

4. A spindle drive comprising the construction defined in claim 1, together with means for yieldingly forcing each idler against the loop in its band to maintain a constant tension in its band.

40 In testimony whereof, I have signed my name to this specification.

JOSEPH W. RANDALL.
